CLAIM

The ornamental design for a beverage container and dispenser, as shown and described.

DESCRIPTION

FIG. 1 is a front and right side perspective view of a beverage container and dispenser showing our new design;

FIG. 2 is a top plan view of the beverage container and dispenser shown in FIG. 1;

FIG. 3 is a bottom plan view of the beverage container and dispenser shown in FIG. 1;

FIG. 4 is a front elevation of the beverage container and dispenser shown in FIG. 1;

FIG. 5 is a left side elevation of the beverage container and dispenser shown in FIG. 1;

FIG. 6 is a right side elevation of the beverage container and dispenser shown in FIG. 1; and,

FIG. 7 is a rear elevation of the beverage container and dispenser shown in FIG. 1.

The representation, in FIG. 1, of the bottle in phantom lines is for environmental structure only and forms no part of the claimed design.
